REFRIGERATING APPARATUS

Richard D. Kneisley, Dayton, Ohio, assignor to
General Motors Corporation, Dayton, Ohio, a
corporation of Ohio

Application March 29, 1935, Serial No. 13,724

2 Claims. (Cl. 211—143)

The present invention relates to shelving for refrigerator cabinets.

An object of the present invention is to provide an improved construction of supports for movable or sliding shelves.

Another object of the invention is to provide supports for such movable or sliding shelves which are readily removable from a refrigerator cabinet for cleaning but which are securely held in place in the cabinet against accidental removal.

A further object of the invention is to provide a unitary construction of which a shelf incorporated therein may be pulled outwardly of a refrigerator cabinet through the door opening thereof like a drawer, to substantially the full extent of its length, so as to expose to view articles supported thereon without stooping to peer in and so that any article on it may be lifted therefrom without having to tilt the article to avoid striking the upper shelf.

In carrying out the foregoing objects it is a still further and more specific object of the present invention to provide a combined support and track for sliding shelves which is constructed or formed of sheet or strap metal so as to facilitate production thereof and reduced manufacturing costs to a minimum.

Further objects and advantages of the present invention will be apparent from the following description, reference being had to the accompanying drawings, wherein a preferred form of the present invention is clearly shown.

In the drawings:

Fig. 1 is a fragmentary vertical sectional view through a refrigerator cabinet of the household type having shelving arrangements constructed in accordance with the invention mounted therein;

Fig. 2 is a fragmentary horizontal view through the cabinet disclosed in Fig. 1 and showing the shelving in normal position;

Fig. 3 is a fragmentary sectional view of the cabinet taken on the line 3—3 of Fig. 2 and showing a front view of the shelving;

Fig. 4 is a view similar to Fig. 2 and shows a modified form of shelving mounted in the cabinet;

Fig. 5 is a sectional view of the modified shelving and is taken on the line 5—5 of Fig. 4; and

Fig. 6 is a view similar to Fig. 3 and showing a front plan view of the modified shelving.

Referring to the drawings, for the purpose of illustration, I have shown in Fig. 1 thereof a refrigerator cabinet of the household type generally designated by the reference character 10.

The cabinet 10 includes a plurality of insulated walls 11 surrounding and forming a compartment 12 having a metal lining 13. The compartment 12 is adapted to be cooled by a cooling element 14 mounted therein in any suitable manner and connected with a refrigerant circulating unit (not shown). The compartment 12 is provided with an access opening 15 which is ordinarily closed by a door (not shown). A plurality of horizontally disposed and vertically spaced apart shelving devices generally designated by the reference character 17 divide the compartment 12 of cabinet 10 into a plurality of superimposed food storage chambers.

Each of the shelving devices 17 includes a pair of horizontally aligned and spaced apart members 19 adapted to be detachably mounted within compartment 12 adjacent the vertical side walls of the lining member 13. The devices 17 also include a movable food supporting shelf portion 21. The members 19 of the shelf device 17 are preferably formed by stamping or punching same from thin gauge sheet or strap metal and these members each have an ear 22 depending therefrom near the front end thereof. The ear portion 22 has an opening therein through which a screw, bolt or the like element 23 extends and which element is secured to the lining 13 in any suitable manner. An ear 24 depending from each of the members 19 at the rear thereof has a finger portion 25 extending horizontally therefrom and forming an elongated slot 26. The slot 26 is adapted to be slipped over the shank portion of a screw, bolt or like element 27, secured to the lining 13 near the rear of compartment 12. The shank portion of the screws or bolts 23 and 27 are surrounded by a collar 30 (see Figs. 2 and 3) which spaces the supporting members 19 the proper distance inwardly of the side walls of the food compartment lining 13. The ears 22 and 24 together with the screws or bolts 23 and 27 serve to removably position the unitary shelf device 17 within compartment 12. The bottom portion of the members 19 is bent outwardly and thence upwardly intermediate the ears 22 and 24, as at 28, and in front of ear 22, as at 29, to form or provide a supporting track. The vertical portion of the members 19 above the ears 22 and 24 is hollowed out, as at 31, to form or provide an elongated horizontally extending opening. The movable or slidable shelf portion 21 of the device 17 includes a pair of rods 32 which extend longitudinally and parallel with the members 19. A plurality of horizontally disposed and spaced apart cross rods 33 are secured at 35

their ends, such as by being welded or soldered, to the rods 32 to form or provide a flat food supporting surface for the shelf 21. The longitudinal rods 32 are adapted to be slidably carried 5 in or on the tracks formed by the bent portions 28 and 29 on members 19. Rods 32 are of a thickness sufficient to bring their top surface up to or in horizontal alignment with the bottom wall of opening 31 when supported on the tracks. The 10 one cross rod 35 at the rear of the shelf portion 21 of device 17 is longer than the other cross rods 33 (see Figs. 2 and 3) and has its ends 36 extending beyond the rods 32 and through the opening 31 in members 19. Extension of the ends 15 36 of cross rod 35 into or through the opening 31 in members 19 serves to provide a stop for preventing removal of the sliding shelf 21 of device 17 from the members and consequently from the cabinet 10 since the ends 36 of rods 35 will strike 20 the front end of the slot 31. The ends 36 of rod 35 in opening 31 together with the manner of supporting the longitudinal rods 32 on members 19 serve to prevent the food supporting shelf portion 21 of device 17 from tilting or moving downwardly out of a horizontal plane when they are 25 slid outwardly of the members 19.

It will be seen that I have provided a novel and improved sliding shelf for refrigerator cabinets and that the shelf 21 may be slid outwardly 30 of compartment 12 to any one of a plurality of positions when the door, which normally closes the compartment access opening 15, is open. The shelf 21 may be slid outwardly a distance equal to the length of the slot 31 whence the ends 36 35 of rod 35 will strike the forward end of slot 31 and prevent further outward movement of the shelf. My sliding shelf while being rigidly mounted within the food storage compartment can be readily removed or detached therefrom for permitting 40 cleaning of the shelf or cleaning of the food storage compartment walls. For example, to remove the unitary sliding shelf device the two screws or bolts 23 at the front of the food storage compartment 12 are all that are required 45 to be removed. After the screws or bolts 23 are removed the supporting or carrying members 19 of the shelf device 17 can be slid forward until the slots 26 in the members 19 clear the screws or bolts 27 at the rear of the food compartment. 50 The unitary shelf device 17 is then free to be removed from the compartment for cleaning or other purposes.

In Figs. 4 to 6 inclusive I have disclosed a modified form of the invention. In this modified form 55 of shelf arrangement a lug or horizontal extension 41 is provided on and at the back of each of the longitudinal rods 32 and these lugs extend into or through the elongated opening 31 in the members 19. Instead of providing an elongated 60 track for the rods 32 the flat sheet metal members 19 of the modified form of shelf arrangement each have an outwardly extending short shelf supporting portion 42 at the front end thereof. The portions 42 together with the lugs 65 41 positioned within the slots 31 serve to prevent detachment of the food supporting shelf 21 from the carrying members 19 of the device 17 and also serve to maintain the shelf 21 in a horizontal plane when same is moved outwardly of the members 19. The modified shelf arrangement disclosed 70 may also be removed or detached from the cabinet 10. To remove the unitary shelf arrangement 17 shown in Figs. 4, 5, and 6 the screws 27 at the rear portion of compartment 12 are removed and the screws 23 at the front of com-

partment 12 are loosened. The rear portion of the supports 19 are then detached from the compartment walls and the front portion thereof may be elevated to cause the vertical slots provided in the front end of members 19 to disengage the screws or bolts 23. The unitary device 17 is then free to be bodily removed from the refrigerator cabinet. 5

Therefore it will be seen that either form of my improved sliding shelf arrangement disclosed 10 can be manufactured at low cost by virtue of the shelf supporting or carrying members thereof being stamped or punched from flat sheet metal which is inexpensive as compared to telescoping tubing or roller and track combinations heretofore employed in the construction of sliding shelves. My sliding shelf arrangement facilitates removal of food products from the storage compartment of a refrigerator cabinet and also facilitates rearrangement of the food products 20 by moving same to a position where they are readily accessible for removal without tilting or striking an upper shelf. The improved shelf arrangements disclosed are rigidly mounted within the refrigerator cabinet so as to prevent vibration 25 of the cooperating parts thereof and the arrangement is such that it can be readily removed from the cabinet to permit cleaning of the shelf device or cleaning of the food storage compartment walls. 30

While the forms of embodiment of the invention as herein disclosed, constitute a preferred form, it is to be understood that other forms might be adopted, all coming within the scope 35 of the claims which follow. 35

What is claimed is as follows:

1. In a slideable shelf unit adapted to be mounted in the food storage compartment of a refrigerator cabinet comprising in combination, sheet metal guide members adapted to be disposed in substantially the same horizontal plane for extension along opposed side walls of the food compartment, means for detachably mounting said guide members against movement relative to said compartment walls, said sheet metal guide members each including a horizontally extended track portion adapted to support a shelf thereon and an integral upwardly disposed portion having an elongated horizontally extending opening therein adapted to receive a part of the shelf for retaining same on the guide members, a shelf having its side edges carried by said shelf supporting track portion of said guide members and having a part thereof projecting outwardly beyond each of its side edges into the elongated opening in 55 said guide members, said shelf having a reticulated food supporting area between its side edges and being slideable relative to said guide members outwardly of the food compartment of the refrigerator cabinet, said projecting parts of said shelf being adapted to engage the upper wall of the elongated opening in said guide members and cooperating with said shelf supporting track portion thereof to prevent tilting of the shelf when same is slid outwardly of the food storage compartment, and said projecting parts of said shelf being adapted to engage the wall of the forward end of the elongated opening in said guide members for limiting movement of the shelf outwardly of the food compartment. 60

2. In a slideable shelf unit adapted to be mounted in the food storage compartment of a refrigerator cabinet comprising in combination, sheet metal guide members adapted to be disposed in substantially the same horizontal plane 65

for extension along opposed side walls of the food compartment, means for detachably mounting said guide members against movement relative to said compartment walls, said sheet metal 5 guide members each including a U-shaped track portion adapted to support a shelf thereon, one leg of the U-shaped track portion of said guide members extending upwardly beyond the other leg thereof and having an elongated horizontally 10 extending opening therein adapted to receive a part of the shelf for retaining same on the guide members, a shelf comprising edge members carried in the U-shaped track portion of the guide members and having a plurality of cross members 15 secured in spaced apart relation along the edge members to provide a food supporting area therebetween, one of said shelf cross members being of greater length than others thereof and

projecting into the elongated opening in said guide members, said shelf being slidable relative to said guide members outwardly of the food compartment of the refrigerator cabinet, the projecting portions of said one of said shelf cross members being adapted to engage the upper wall of the elongated opening in said guide members and cooperating with said U-shaped track portion of said guide members to prevent tilting of the shelf when same is slid outwardly of the food 10 storage compartment, and said projecting portions of said one shelf cross member also being adapted to engage the wall at the forward end of the elongated opening in said guide members for limiting movement of the shelf outwardly of 15 the food compartment.

RICHARD D. KNEISLEY.
